JOHN L. McMILLAN, OF SYRACUSE, NEW YORK, ASSIGNOR TO McMILLAN BOOK COMPANY, OF SYRACUSE, NEW YORK, A CORPORATION OF NEW YORK.

GUIDE-PLATE FOR LOOSE-LEAF BINDERS

Application filed June 27, 1928. Serial No. 288,550.

This invention relates to a new and improved guide plate for loose leaf binders.

In the use of loose leaf binders of the type usually called post binders it is frequently necessary to remove from the binder a sheet which is located a considerable distance below the top sheet. In order to accomplish this it is necessary to remove from the posts all of the sheets which are positioned above the sheet which it is desired to remove. When this is done a considerable amount of time and manipulation is necessary to replace on the posts the sheets which have been removed because when a considerable number of sheets are to be replaced it is difficult, if not impossible, to align the holes in the sheets so that they may be all replaced at the same time.

It is also difficult in books of this character to replace in the proper position the upper cover which, of necessity, has been removed when it is desired to remove sheets from the book.

The main object of my invention is to provide a device to be used in conjunction with a loose leaf post binder which will permit the removal from the posts of any desired number of sheets and the replacement of the same in one operation.

Another object is to provide a device which will also act as a guide and positioning means for the cover which has been removed when the same is replaced in position.

Another object is to provide a device which will permit the use in a loose leaf binder of sheets which have recesses for the reception of the posts, which recesses are the same width as the posts so that the sheets may be placed on the posts without the necessity of first distorting them in order to permit the insertion of the posts.

Other objects and advantages relate to the size, shape and association of parts all as will more fully appear from the following description taken in connection with the accompanying drawings in which:

Figure 1 is a perspective view, partially broken away, of a post binder in the open position and with my device in place.

Figure 2 is a perspective view of my guide plate.

Figure 3 is a section on line 3—3 of Figure 1.

Figure 4 is a section on line 4—4 of Figure 3.

Figure 5 is a section on line 5—5 of Figure 3.

It will be obvious that my device can be used in conjunction with any type of loose leaf post binder whether the post be rigid or flexible but for the purpose of explaining the functioning of my device I have here shown a flexible post binder of the type disclosed in a co-pending application filed by me and Paul O. Unger, December 27, 1927, Serial No. 242,744 in which the binder consists of an upper housing —1— and a lower housing —2— hingedly connected to upper and lower covers —3— and —4— respectively between which are confined sheets —5—.

The upper housing —1— consists of a bottom plate —6— U-shaped in cross section and having at either end holes 7—7 which holes carry on their inner edges depending curved guide pieces 8—8. One edge of bottom plate —6— carries a plurality, in this case four, 70 projecting eye portions —9— between which are received eye portions —10— of cover —3—.

A pintle (not shown) is passed through eye portions —9— and —10— to hold the same together and to create what is in effect a piano hinge. A cover —12— of the

same cross section as bottom plate —6— is fitted on bottom plate —6— to form a hollow approximately rectangular casing. An end plug —13— is positioned in one end of the

casing formed by cover —12— and bottom plate —6— and carries on its inner face a socket at —15— for a purpose hereinafter to be described. Another end plug —14— is positioned in the opposite end of the casing

and is formed with a cylindrical hole at —16— for a purpose hereinafter to be described. A bearing plate —18— is positioned against the inner face of end plug —14—. A rod —19— extends the length of casing formed by cover —12— and bottom plate —6— adjacent to one side thereof and having one end journaled in socket —15— and the other end journaled in bearing plate —18—.

The rod —19— is sufficiently long to extend 100

into the hole —16— and the part —20— of rod —19— which extends into hole —16— is square in cross section for engagement with a key or crank (not shown). One end of rod —19— carries a right hand thread —21— and the opposite end of rod —19— carries a left hand thread —22—. Locking nuts 23 and 24 are carried on the threaded ends —21— and —22— respectively of rod —19— and are of such a shape that the housing —1— will prevent their rotary movement when the rod —19— is rotated. A guide plate —25— is positioned in housing —1— at approximately the center point thereof, and a guide rod —26— extends through guide plate —25— and bears on end plugs —13— and —14—. Guide rod —26— is positioned parallel to rod —19— and adjacent the opposite side of housing —1—. Flexible posts —27— and —28— are inserted into housing —1— through holes —7—.

These flexible posts —27— and —28— are similar in construction and are preferably made of tongue and groove links —29— held together by pintles —30—. The inner ends of flexible posts —27— and —28— carry guide links —31— and —32— respectively, said guide links being movably mounted on guide rod —26—. Guide rod —26— also carries a spring retaining collar —33— abutting against end plug —13— and a slideable spring retaining collar —33'— normally abutting against guide link —31—. A spring —34— is interposed between the spring retaining collar —33— and the spring retaining collar —33'—, said spring —34— encircling guide rod —26—. Similarly a spring retaining collar —35— is carried on guide rod —26— abutting against end plug 14, and a similar spring retaining collar —36— is carried on guide rod —26— and is slideable thereon and normally abuts against guide link —32—. Similarly a spring —37— encircles guide rod —26— and bears against spring retaining collars —35— and —36—.

Lock nuts —23— and —24— extend downwardly through holes 7—7 in bottom plate —6— and have curved faces adjacent flexible posts —27— and —28— respectively. The proportions of lock nuts —23— and —24— are such that when they are moved inwardly by the rotation of rod —9— they will be forced against flexible posts —27— and —28— to hold the same locked in position. The socket —15— is of a sufficient depth with relation to the length of rod —19— that a limited longitudinal movement of rod —19— is permitted so that in all cases lock nuts —23— and —24— will simultaneously contact and lock flexible posts —27— and —28—. When the lock nuts —23— and —24— are moved outwardly they will be stopped by the outside edges of holes 7—7 in a position to act as guides for flexible posts —27— and —28— when they are moved in and out

through holes 7—7. A protecting plate —37— having spaced holes —38— and —39— for permitting the passage of flexible posts —27— and —28— is positioned on the underside of bottom plate —6— and is formed so as to register with the bottom edges of guides 8—8 and to act as a protecting plate for leaves —5—. Protecting plate —37—, bottom plate —6—, end plug —13— and cover —12— are fastened together by means of rivets —40—. Similarly at the other end protecting plate —37—, bottom plate —6—, end plug —14— and cover —12— are fastened together by means of rivets —41—.

The lower housing —2— is formed with an upper plate —42— which is U-shaped in cross section and which carries spaced holes —43— and —44— positioned so as to register with holes 7—7 in housing —1—. Upwardly extending curved guides —45— and —46— are positioned on the inner edges of holes —43— and —44— respectively. One edge of top plate —42— carries a plurality, in this case four, of projecting eye portions between which are received registering eye portions of cover —4— which eye portions are held together to form a hinge by a pintle. The hinge construction for housing —2— is not shown in the drawing but is similar in all respect to the hinge construction of housing —1— previously described. A bottom plate —47— similar in cross section to top plate —42— is fitted on plate —42— to form a hollow approximately rectangular casing. An end plug —48— is positioned in the end of the casing formed by top plate —42— and bottom plate —47— and carries on its inner face a socket not shown for a purpose hereinafter described. A bearing plate —50— is positioned adjacent the inner face of end plug —48—. Another end plug —51— is positioned in the opposite end of the casing formed by top plate —42— and bottom plate —47— and is provided with a cylindrical hole —52— for a purpose hereinafter described. A bearing plate —53— is positioned adjacent the inner face of end plug —51—. A guide plate —54— is positioned in the casing formed by top plate —42— and bottom plate —47— at approximately the center point thereof. A rod —55—, carrying on one end a right hand thread —56— and on the opposite end a left hand thread —57—, is positioned adjacent one longitudinal side of the casing formed by top plate —42— and bottom plate —47— and has one end journaled in bearing plate —50—. The other end of rod —55— is journaled in bearing plate —53— and has an extension —58—, square in cross section, extending into cylindrical hole —52—. The square end —58— is designed to receive a key or crank (not shown) by which rod —55— is rotated. Nuts —59— and —60— are threaded on threads —57— and —56— respectively. The opposite ends

of flexible posts —27— and —28— heretofore described are inserted through holes —44— and —45— and are connected by links —61— and —62— to nuts —60— and —59— respectively. A protecting plate —63— having spaced holes —64— and —65— registering with holes —43— and —44— respectively is positioned on the upper side of top plate —42— and is of such a form and shape as to have its upper surface adjacent the upper edges of guides —45— and —46—. Protecting plate —63—, top plate —42—, and plug —48— and bottom plate —47— are secured together by rivet —66—. Similarly protecting plate —63—, top plate —42—, end plug —51— and bottom plate —47— are secured together by rivet —67—.

For use with the binder I provide a guide plate —68— in this case substantially U-shaped in cross section to conform to one face of housing —1—. It will be understood that the exact shape of guide plate —68— will depend upon the type of binder with which it is to be used, the requirement being that its shape shall conform to the shape of one face of the housing with which it is to be used.

On the bottom of guide plate —68— I provide a plurality, in this case shown as two, of downwardly extending posts —69— which are preferably of the extensible type having a base portion —70— affixed to guide plate —68— and an end portion —71— threaded into base portion —70— so that, if desired, end section —71— may be unscrewed from base section —70— and a filler section, not shown, screwed into base section —70— and receiving in its other end end section 71 for the purpose of making the posts of greater length. I also provide in guide plate —68— a plurality, in this case shown as two, of apertures —72—.

In assembling my device I place one of the guide plates —68— on housing —2— and place thereupon sheets —5— which are provided with apertures through which posts —69— extend and which also are provided with apertures registering with holes —72—. I then place a second guide plate —68— on the upper surface of the topmost sheet —5— with its posts —69— extending downwardly through the apertures in sheets 5 which are in registration with the holes 72 in the guide plate 68 which is in position on housing —2—. Holes —72— in guide plates —68— are provided so that if it is desired the posts —69— in one guide plate —68— will extend through the sheets 5 into holes 72 and vice versa to give greater rigidity to the book when the same is in the locked position.

With the two guide plates 68 in position as just described I place housing —1— in registration with the guide plate 68 which is in position on the topmost sheet 5 and I then rotate the rod —55— in the proper direc-

tion to draw nuts 59 and 60 towards the center of housing —2— which will result in shortening the posts between housings 1 and 2 and will lock the different parts of the structure together.

Similarly when the book is in the locked position and it is desired to open the same the rod —55— is rotated in the opposite direction to move nuts 59 and 60 away from the center of the housing and force portions of flexible posts 27 and 28 out of the housing thereby increasing their length between housings 1 and 2 so that housing —1— may be lifted off of its guide plate 68.

When the book is in the last described open position any desired number of sheets 5 may be removed therefrom while being retained in position on guide plate 68. When it is desired to return these sheets 5 to the book the operation is very much facilitated due to the fact that they are in position on guide plate 68 and the posts 69 carried by guide plate 68 may be easily inserted into the proper apertures in the sheets 5.

The object of having guide plate 68 conformed to one side of housing —1— is that when the book is being closed one edge of housing —1— may be placed over the edge of guide plate 68 and as the book is closed housing —1— will move downwardly into registration with guide plate 68 and into the proper position for permitting locking of the book.

It will be understood that either housing —1— or housing 2 may be removed from its guide plate 68 depending upon which side of the book it is desired to open.

It will also be understood that slots 73 are provided in sheets 5 for the reception of flexible posts 27 and 28 and by the use of guide plates 68 it is possible to have slots 73 of such a shape that posts 27 and 28 may enter therein without any distortion of sheets 5. The advantage of being able to use slots 73 of such shape is that sheets 5 may be easily and readily used in a typewriter which is not true of the ordinary apertures now provided for use with post binders, such last mentioned apertures being of a practically circular shape with a slit extending to the edge of the sheet.

It will also be understood that the number of posts 69 carried by a guide plate 68 may be varied as may the number of apertures 72 or if desired apertures 72 may be eliminated. It will also be understood that the exact size and shape of guide plates 68 may be varied to accommodate them to different sizes, types and shapes of post binders without departing from the spirit of my invention, for altho I have shown and described a specific structure and form of part as an exemplification of an embodiment of my invention I do not desire to restrict myself to the exact size, shape or arrangement

of parts as various changes may be made within the scope of the appended claims.

I claim:

1. In a loose leaf book, a pair of opposed convex back members, covers hinged to the back members and a concave plate in contact with the inner face of each back member and removable therefrom, and having a plurality of posts adapted to extend through openings in loose leaves.
2. In a loose leaf book, a pair of opposed convex back members, covers hinged to the back members and a concave plate in contact with the inner face of each back member and removable therefrom, and conforming substantially to the convexity of the back member, and having a plurality of posts adapted to extend through openings in loose leaves.
3. In a loose leaf book, a pair of opposed back members having their opposite sides curved, covers hinged to the back members, and a plate having its outer side curved in substantial conformity to the back member and adapted to engage the inner face of such back member and center the same, and having a plurality of posts adapted to extend through openings in loose leaves.
4. In a loose leaf book, a pair of opposed back members, covers hinged to the back members, and a plate having outwardly extending sides adapted to receive a back member therebetween, said plate having a plurality of posts adapted to extend through openings in loose leaves.
5. In a loose leaf book, a pair of opposed back members, covers hinged to the back members, and a plate having an outwardly extending side adapted to engage an edge of a back member and having a plurality of posts adapted to extend in apertures in loose leaves.

In witness whereof I have hereunto set my hand this 21st day of June, 1928.

JOHN L. McMILLAN.
